FOLDING LARYNGOSCOPE

Filed July 8, 1946

UNITED STATES PATENT OFFICE

2,433,705

FOLDING LARYNGOSCOPE

Harry E. Palmeter, Auburn, N. Y., assignor to
William N. Allyn, Skaneateles, N. Y.

Application July 8, 1946, Serial No. 681,942.

7 Claims. (Cl. 128—10)

1

The present invention appertains to instruments used in the practice of laryngoscopy, and more especially to folding laryngeal speculums of the general type disclosed in Patent No. 2,289,226, granted July 7, 1942, to Richard von Foregger.

The primary object of the invention is to provide a new and improved detachable hinge joint for connecting the laryngeal blade to the usual supporting battery handle of such instruments.

A further object of the invention is to provide an exceedingly simple and quickly-detachable hinge joint as aforesaid, which allows the laryngeal blade to be folded to a position lying relatively close and parallel to the battery handle or other support, and which permits the blade to be easily detached from the handle and re-attached thereto, at will, when in such folded position, while also permitting the blade to be swung to and firmly held in an extended position, projecting laterally from the handle, as required under normal conditions of use.

Another object of the invention is to provide a detachable hinge connection between the laryngeal blade and its supporting handle, having incorporated therein a plurality of yieldable detents which may be selectively employed to detachably connect the blade to the handle, and to hold the blade rigid in its extended position, respectively, at least one of said detents coacting with a fixed hinge pin about which the blade is movable to and from the folded position.

A still further object of the invention is to provide an improved detachable hinge connection between the foldable laryngeal blade and its supporting handle which admits of the use of cooperative electrical circuit making and breaking contacts on the blade and the handle, respectively, to control the usual electrical circuit to an electric lamp carried by the blade, said contacts serving to interrupt the lamp circuit responsive to folding movement of the blade, and to automatically close the lamp circuit responsive to movement of the blade to its extended position of use.

Other and further objects and advantages of the invention will be hereinafter described and the novel features thereof defined in the appended claims.

In the drawing:

Fig. 1 is a view in side elevation of a laryngoscope embodying my improved detachable hinge joint, and showing the laryngeal blade connected to the battery handle, with the blade shown in

full lines in its extended position, and in broken lines in its folded position;

Fig. 2 is a fragmentary composite view in side elevation, showing the detachable hinge joint in a detached condition and ready for re-attachment to connect the laryngeal blade to the battery handle;

Fig. 3 is a fragmentary view, partly in vertical section through the detachable hinge joint, and partly in elevation, and more particularly showing the details of the detents and the circuit making and breaking contacts;

Fig. 4 is a sectional view taken on the line 4—4 of Fig. 3; and

Fig. 5 is a fragmentary view in bottom plan of the hinged end of the laryngeal blade.

Like reference characters designate corresponding parts in the several figures of the drawing, wherein 1 generally denotes a supporting handle which is preferably of the type containing one or more dry-cells of the flashlight cell type, which constitute a source of electrical energy. To the upper end of the battery handle 1, a laryngeal blade generally designated 2 is pivotally connected for swinging movements from a folded position lying closely adjacent and parallel to the battery handle 1, as shown in broken lines in Figure 1 of the drawing, to an extended position projecting approximately at a right angle to the battery handle, but preferably inclining downwardly slightly from a horizontal position, as shown in full lines in this figure. The laryngeal blade 2 carries a small but powerful electric lamp 3 adjacent to the free end thereof, said lamp being connected in circuit with the dry-cells, as shown in Fig. 3, within the battery handle 1, through suitable circuit-controlling instrumentalities which are included in the pivotal joint between the laryngeal blade and the battery handle, as will hereinafter be more fully described.

It will be understood, of course, that instead of employing a supporting handle 1 having a self-contained source of electrical energy, the handle 45 may be provided with an extension cord which can be plugged in to any convenient electrical outlet.

Referring particularly to Figures 1 and 3 of the drawing, the battery handle 1 includes a cylindrical body or casing 4 which is provided with a cap 5 detachably connected to its lower end, and which, on detachment of the cap, permits removal and replacement of the dry-cells contained in the casing 4, said dry-cells being 55 designated 6 and being shown in Figure 3. At

the upper end of the body or casing 4, there is provided a head 7 which may be permanently attached to the casing, or removably connected thereto by suitable screw fastenings 8 or other instrumentalities, as preferred. The head 7 is provided at its upper end with a pair of laterally spaced upright ears designated 9, 9 which project upwardly therefrom in parallel relation to each other, as more particularly shown in Figure 4 of the drawing. Fixed to the ears 9, 9 and extending transversely therethrough and across the space therebetween at the upper forward corner thereof is a stationary hinge pin designated 10.

The laryngeal blade 2 is provided at its rear end with a complementary head 11 fixed thereto and adapted to be detachably engaged with the head 7 of the battery handle 1. For this purpose, the head 11 is narrowed at its lower end so as to form a knuckle 12 which may be inserted between the ears 9, 9 of the head 7. At its forward edge, the knuckle is provided with a transverse recess or slot 13 which is adapted to receive the hinge pin 10 therein when the head 11 is attached to the head 7. The recess or slot 13 preferably inclines downwardly somewhat from the forward edge of the knuckle 12, so that the base of the recess is disposed at a slightly lower elevation than the extreme forward end of the recess. This facilitates the reception of the hinge pin into the recess when the complementary heads 11 and 7 which form the detachable joint between the laryngeal blade and the battery handle, are connected together by relative movement of the parts in the general direction represented by the broken arrow in Figure 2 of the drawing. Also, it aids in preventing the parts from becoming inadvertently disconnected when the laryngeal blade is moved to the extended position shown in full lines in Figure 1. As will be noted from the relative position of the parts as seen in Figure 2, the connection of the laryngeal blade to the battery handle can be best made when the laryngeal blade is in a substantially folded and downwardly inclined position. To afford adequate clearance in making the connection of the knuckle 12 with the hinge pin 10, the lower forward corner of the knuckle is preferably beveled, as at 14, which also serves to permit the laryngeal blade to be swung to a fully folded position lying closely adjacent and parallel to the battery handle 1, as shown in broken lines in Figure 1, without jamming the knuckle against the portion of the upper end of the head 7 which lies between the ears 9, 9.

In order to prevent the laryngeal blade from becoming inadvertently detached from the battery handle, both when the blade is folded as well as extended, the head 11 is provided with a yieldable detent which coacts with the hinge pin 10, said detent including a spring-pressed ball 15 which is so disposed as to partially obstruct the throat or mouth of the recess 13 near the forward end thereof, and engageable with the hinge pin 10. The ball 15 is preferably disposed in a cup-shaped container or housing 16 which is recessed in the head 11 substantially midway between the opposite ends of the recess 13. The outer end of the housing 16 is turned in slightly or otherwise constricted, to prevent the ball 15 from becoming displaced from the housing 16, while at the same time, allowing the ball to be projected slightly beyond the extreme end of the housing by the pressure of a spring 17 seated at one end against the bottom of the housing, and at its other end against the ball 15. Thus,

in connecting the laryngeal blade to the battery handle, the ball 15 will be depressed sufficiently as the head 11 is engaged with the head 7, during which engagement the hinge pin 10 is pressed inwardly into the recess 13 so as to pass beyond the ball until the pin seats against the bottom of the recess 13. When so seated, the ball 15 will be projected slightly in front of the hinge pin 10, and will be maintained in such projected position by the pressure of the spring 17 which is stiff enough to prevent inadvertent displacement of the hinge pin from the recess 13, while allowing the ball to yield sufficiently when a substantial pressure is applied against the same on displacing the parts of the detachable heads 11 and 7 in a direction opposite to the movement which connects the heads, for the purpose of disconnecting the laryngeal blade from the battery handle.

After connecting the laryngeal blade to the battery handle in the manner previously described, the blade may then be swung to the extended position shown in full lines in Figure 1, in which position the head 11 at each side of the knuckle 12 assumes a flat abutting engagement with the extreme upper ends of the ears 9, 9, which are likewise flat, as indicated in the drawing. In order to maintain the laryngeal blade in the extended position aforesaid, additional detents are preferably provided, said detents preferably comprising two spring-pressed balls designated 18 and 19 respectively. The balls 18 and 19 are both preferably mounted in a single housing 20 which in turn is mounted in an opening 25 extending transversely through the knuckle 12 of the head 11 on the laryngeal blade 2. The extreme opposite ends of the housing 20 are constricted in a manner similar to the housing 16, to prevent the balls from becoming displaced from the housing, and between the balls 18, 19, there is disposed a coil spring 21 having its opposite ends abutting against the respective balls 18 and 19. The balls are thus normally projected slightly beyond the opposite ends of the housing 20, and hence beyond the opposite sides of the knuckle 12, and as the laryngeal blade is swung to the extended position, the balls 18 and 19 will engage and seat in recesses 22 and 23 respectively, formed in the inner faces of the respective ears 9, 9 of the head 7. The spring 20 should have sufficient pressure upon the balls 18, 19 so as to maintain firm engagement of the balls with the recesses 22, 23 when the laryngeal blade is moved to the extended position, while the balls are yieldable sufficiently when a substantial pressure is applied to the laryngeal blade to disengage the balls from the recesses as the blade is moved to the folded position shown in dotted lines in Figure 1.

It will be understood from the foregoing that the pivotal movement of the laryngeal blade relative to the battery handle 1 can always be effected so long as the hinge pin 10 is seated fully in the recess 13, said hinge pin serving as the axis or fulcrum for such pivotal movement, while the ball detents are selectively operative to maintain the laryngeal blade in its connected condition with respect to the battery handle, and in an extended position of the blade, respectively.

As previously mentioned, an electric lamp designated 3 is mounted on the laryngeal blade at the forward or free end thereof, and accordingly, it is necessary to establish an electrical circuit between the lamp and the battery or dry-cells 6 contained in the battery handle, while at the

same time permitting the laryngeal blade, with the lamp, to be disconnected, at will, from the battery handle. To this end, the lamp 3 is mounted in a lamp socket 24 to which a conductor 25 is connected at one end, the conductor 25 leading through a small conduit 26 extending along the outside of the blade and attached thereto. At the rear end of the blade, the conductor 25 leads through the head 7 in which a lateral passage is formed, extending to about the center of the head. At the center of the head 11, the head is counterbored, as at 27, said counterbore extending to the extreme lower end of the knuckle 12. Disposed in the lower end of the counterbore 27 is an insulating sleeve 28 which surrounds a central fixed contact member 29, to the inner end of which the conductor 25 is connected. Thus, the contact member 29 is insulated from the head 11 and the laryngeal blade, as well as the conductor 25 is insulated therefrom.

The head 7 of the battery handle 1 is provided with a counterbore extending completely therethrough, and in which is mounted an insulating sleeve 30 of fiber, Bakelite, or other suitable material. The lower end of the sleeve 30 projects into a recess 31 formed in the inner end of the head 7, and threadedly received on the extreme lower end of the sleeve 30 is a metal cap 32 having abutting engagement with an insulating washer 33 surrounding the sleeve 30 and abutting against the inner bottom side of the recess 31. Slidably disposed in the upper end of the insulating sleeve 30 is a movable contact member 34 which is seated upon the upper end of a coil spring 35 disposed within the sleeve 30, the lower end of the spring 35 seating against the cap 32 which extends more or less beyond the bottom of the head 7 to an extent sufficient to make good contact with the central pole of the dry-cell or flashlight battery 6.

When the laryngeal blade 2 is disconnected from the battery handle 1, the movable contact member 34 will be projected slightly beyond the upper end of the head 7 on the battery handle, said upward movement being limited by an enlarged head 37 formed on the inner end of the contact member 34 to prevent displacement of the contact member from the head of the battery handle. When the laryngeal blade is connected to the battery handle and then swung to its extended position, the contact member 29 in the head 11 of the laryngeal blade will engage the contact member 34 in the head 7 of the battery handle, and as the laryngeal blade approaches its fully extended position, the contact member 34 will be depressed against the pressure of the spring 35 until the blade assumes its fully extended position and is locked in such position by engagement of the ball detents 18, 19 with the recesses 22, 23. A circuit is thus established from the dry-cells or batteries in the battery handle, to the lamp 3, causing the lamp to be illuminated or energized, it being understood that the opposite pole of the batteries or dry-cells, together with one side of the lamp 3, being grounded through the laryngeal blade and the battery handle, which are preferably made of metal, to complete the electrical circuit.

When the laryngeal blade is folded to the position shown in broken lines in Figure 1, the contact member 34 will become automatically disengaged from the contact member 29 before reaching the completely folded position, thus interrupting the circuit to the lamp 3 so long as the laryngeal blade remains in such folded position

or when it is completely disconnected from the battery handle.

It will be readily apparent that laryngeal blades of different sizes and/or types may be readily interchanged for use with a common battery handle when the blades and the battery handle are provided with detachable hinge joints of the type hereinbefore described. This is particularly desirable in the use of laryngoscopes when used for the examination of patients of different ages ranging from small children to adults. Also, the removability of the laryngeal blade or blades enables the same to be sterilized more conveniently after use.

While the specific details have been herein shown and described, my invention is not confined thereto as changes and alterations may be made without departing from the spirit thereof as defined by the appended claims.

20. I claim:

1. An instrument of the class described, comprising a supporting handle having a pair of laterally spaced ears extended from one end thereof in parallel relation to each other, and having a pin fixed to said ears and extended transversely therebetween, a laryngeal blade having a part at one end thereof adapted to be received between the ears aforesaid, said part having a recess in one edge thereof for receiving the pin therein to detachably and pivotally connect the blade to the handle, and yieldable means partly obstructing the open end of the recess and coacting with the pin after the pin is seated in the recess for yieldably maintaining the blade in its connected condition with the handle, while permitting detachment thereof from the handle upon application of a substantial pressure to displace the pin past the yieldable means and out of the recess.

40. 2. An instrument of the class described, comprising a supporting handle having a pair of laterally spaced ears extended from one end thereof in parallel relation to each other, and having a pin fixed to said ears and extended transversely therebetween, a laryngeal blade having a part at one end thereof adapted to be received between the ears aforesaid, said part having a recess in one edge thereof for receiving the pin therein to detachably and pivotally connect the blade to the handle, and yieldable detent means partly obstructing the open end of the recess and coacting with the pin after the pin is seated in the recess for yieldably maintaining the blade in its connected condition with the handle, while permitting detachment thereof from the handle upon application of a substantial pressure to displace the pin past the yieldable means and out of the recess.

60. 3. An instrument of the class described, comprising a supporting handle having a pair of laterally spaced ears extended from one end thereof in parallel relation to each other, and having a pin fixed to said ears and extended transversely therebetween, a laryngeal blade having a part at one end thereof adapted to be received between the ears aforesaid, said part having a recess in one edge thereof for receiving the pin therein to detachably and pivotally connect the blade to the handle, yieldable means partly obstructing the open end of the recess and coacting with the pin after the pin is seated in the recess for yieldably maintaining the blade in its connected condition with the handle, while permitting detachment thereof from the handle upon application of a substantial pressure to displace the pin past

the yieldable means and out of the recess, and said part of the blade which is receivable between the ears, and the ears, respectively, having co-acting yieldable detent means for rigidly holding said blade in an extended position when pivotally swung to such position, while permitting pivotal movement of said blade to a folded position upon application of a substantial pressure sufficient to release the latter yieldable detent means.

4. An instrument of the class described, comprising a supporting handle, a laryngeal blade, means for pivotally and detachably connecting said laryngeal blade to said handle, with the blade pivotally movable about an axis generally transverse to the central axes of the handle and the blade, from a folded position lying closely adjacent and substantially parallel to said handle, to an extended position projecting substantially normal to the handle, said connecting means comprising complementary heads on the handle and blade respectively, one of said heads having a stationary hinge pin carried thereby and the other of said heads having a recess therein extending inwardly from the front face of the head and inclining downwardly therefrom when the laryngeal blade is in a fully extended position, said recess displaceably receiving the hinge pin therein so as to form a detachable hinge joint between the blade and the handle, but preventing displacement of the hinge pin therefrom except when the blade occupies a position intermediate the fully extended and fully folded positions, and means for releasably holding said blade in its extended position.

5. An instrument of the class described, comprising a supporting handle, a laryngeal blade, means for pivotally and detachably connecting said laryngeal blade to said handle, with the blade pivotally movable about an axis generally transverse to the central axes of the handle and the blade, from a folded position lying closely adjacent and substantially parallel to said handle, to an extended position projecting substantially normal to the handle, said connecting means comprising complementary heads on the handle and blade respectively, one of said heads having a stationary hinge pin carried thereby and the other of said heads having a recess therein for displaceably receiving the hinge pin therein so as to form a detachable hinge joint between the blade and the handle, yieldable means partially obstructing the open end of the recess aforesaid and coacting with the hinge pin on the other head after the hinge pin is seated in the recess, for maintaining the heads in an attached condition while permitting pivotal movement of the heads, and consequently the blade and the handle, relative to each other, and means for releasably holding said blade in its extended position.

6. An instrument of the class described, comprising a supporting handle, a laryngeal blade, means for pivotally and detachably connecting said laryngeal blade to said handle, with the blade pivotally movable about an axis generally

transverse to the central axes of the handle and the blade, from a folded position lying closely adjacent and substantially parallel to said handle, to an extended position projecting substantially normal to the handle, said connecting means comprising complementary heads on the handle and blade respectively, one of said heads having a stationary hinge pin carried thereby and the other of said heads having a recess therein for displaceably receiving the hinge pin therein so as to form a detachable hinge joint between the blade and the handle, yieldable detent means partially obstructing the open end of the recess aforesaid and coacting with the hinge pin on the other head after the hinge pin is seated in the recess, for maintaining the heads in an attached condition while permitting pivotal movement of the heads, and consequently the blade and the handle, relative to each other, and means for releasably holding said blade in its extended position.

7. An instrument of the class described, comprising a supporting handle, a laryngeal blade, means for pivotally and detachably connecting said laryngeal blade to said handle, with the blade pivotally movable about an axis generally transverse to the central axes of the handle and the blade, from a folded position lying closely adjacent and substantially parallel to said handle, to an extended position projecting substantially normal to the handle, said connecting means comprising complementary heads on the handle and blade respectively, one of said heads having a stationary hinge pin carried thereby and the other of said heads having a recess therein for displaceably receiving the hinge pin therein so as to form a detachable hinge joint between the blade and the handle, yieldable detent means including a spring pressed ball partially obstructing the open end of the recess aforesaid and coacting with the hinge pin on the other head after the hinge pin is seated in the recess, for maintaining the heads in an attached condition while permitting pivotal movement of the heads, and consequently the blade and the handle, relative to each other, and means for releasably holding said blade in its extended position.
